(57) **CLAIM**

The ornamental design for a wristwatch holder with lid and interchangeable ring, as shown and described.

DESCRIPTION

FIG. 1 is a top perspective view of the base of a wristwatch holder with lid and interchangeable ring, the left side of the base being a mirror image of the right side.

FIG. 2 is a top perspective view of the interchangeable ring thereof, the left side of the interchangeable ring being a mirror image of the right side.

FIG. 3 is a bottom perspective view of the interchangeable ring thereof.

FIG. 4 is a top view of the lid thereof.

FIG. 5 is a bottom perspective view of the lid thereof.

FIG. 6 is a top perspective view thereof in a closed position; and,

FIG. 7 is an exploded view thereof.

The broken lines in the drawings represent environmental subject matter and form no part of the claimed design.

1 Claim, 3 Drawing Sheets
